UNITED STATES PATENT OFFICE.

MIRIAM MONTGOMERY, OF MANKATO, MINNESOTA.

ANTICOLIC-NURSER.

1,165,275.

Specification of Letters Patent. Patented Dec. 21, 1915.

Application filed April 26, 1915. Serial No. 23,946.

To all whom it may concern:

Be it known that I, MIRIAM MONTGOMERY, a citizen of the United States, residing at Mankato, in the county of Blue Earth and State of Minnesota, have invented new and useful Improvements in Anticolic-Nursers, of which the following is a specification.

Infants are oftentimes troubled with flatulence, colic and indigestion as a result of too rapid a flow of milk from the breast of nursing women, and it is the object of this invention to avoid such trouble whereby the infant can nurse with comfort.

The invention contemplates the provision of a breast shield constructed from suitable elastic material having a restricted central opening to receive the nipple and embrace the latter with sufficient pressure to prevent a rapid flow of the milk.

Other objects will appear as the nature of the invention is better understood from the following description when taken in connection with the accompanying drawing.

In the drawing forming part of this application, like numerals of reference indicate similar parts in the several views and wherein:

Figure 1 is a top plan view. Fig. 2 is a bottom plan view. Fig. 3 is a sectional view taken on line *a—a* of Fig. 1. Fig. 4 is a section taken on line *b—b* of Fig. 1.

The device forming the subject matter of my invention comprises a semispherical body 5, constructed from any suitable elastic material, preferably rubber of the desired thickness. The device is to be fitted over the breast of nursing women, and provided with a restricted central opening 6 to admit the nipple, the edges of the opening through which the inherent elasticity of the material from which the device is constructed embracing the nipple with sufficient pressure to prevent a too rapid flow of milk from the breast, which quite often proves injurious to the infant, causing the latter to suffer from flatulence, colic and indigestion. The body portion 5 is slit as at 7 from the edge of the opening 6, and covering said slit is a strip 8 of relatively thin material of greater elasticity than the material from which the body 5 is constructed, the strip 8 permitting an

adjustment of the opening 6 when necessary, also adding to the effectiveness of the device by increasing the pressure upon the nipple for the purpose hereinabove stated. The 55 strip 8 may be secured to the body portion 5 in any suitable manner, preferably by vulcanizing the latter to the body portion 5 so as to form an integral part thereof, and the strip 8 may be of the same color as the body 60 portion 5, thereby adding to the general appearance of the device. Irrespective of the manner in which the strip 8 is secured to the body portion 5 the strip must be arranged 65 to provide a perfectly smooth surface with the surface of the body portion 5 so as not to interfere or injure the lips of the infant while nursing. The device may be made in any size or in several sizes, it being understood, however, that the body portion 5 is 70 constructed to snugly fit over the breast with a view of holding the device in proper position and is not intended to exert any pressure whatever upon the breast.

It is believed that from the foregoing description the nature and advantages of the invention will be thoroughly understood without requiring a more extended explanation and therefore the same has been omitted. However I desire to have it understood that 80 I do not limit myself to the precise construction herein illustrated, as various changes may be made in the manufacture of the device when desired as fall within the scope of the appended claims.

What is claimed is:

1. A breast shield constructed from elastic material and comprising a semispherical body having an opening therein and adapted to fit over the breast and exert pressure 90 around the nipple for the purpose described.

2. A breast shield constructed from elastic material and comprising a body to fit over the breast and having a restricted central opening to embrace the nipple to exert pressure 95 around the latter for the purpose described.

3. A breast shield constructed from elastic material and comprising a semispherical body having a central restricted opening, and a portion of said body adjacent said 100 opening having greater elasticity than the remaining portion of the body.

4. A breast shield constructed from elastic material comprising a semispherical-shaped body having a restricted central opening, said body being slit from its opening for a short distance, and the strip of material having greater elasticity than said body covering the said slit.

In testimony whereof I affix my signature in presence of two witnesses.

MRS. MIRIAM MONTGOMERY.

Witnesses:

J. F. THOMPSON,
H. M. HAUCK.
